ATTORNEYS

United States Patent Office.

AMORY EDWARDS, OF ELIZABETH, NEW JERSEY, ASSIGNOR TO UNION METALLIC-CARTRIDGE COMPANY, OF BRIDGEPORT, CONNECTICUT.

Design No. 3,233, dated November 10, 1868.

DESIGN FOR A TRADE-MARK

The Schedule referred to in these Letters Patent and making part of the same.

To all whom it may concern:

Be it known that I, AMORY EDWARDS, of Elizabeth, in the county of Union, and State of New Jersey, have invented a new and improved Design for Trade-Mark; and I do hereby declare that the following is a full, clear, and exact description thereof, which will enable others skilled in the art, to make and use the same, reference being had to the accompanying drawing, forming part of this specification.

This invention relates to a peculiar device, or cipher, or figure to be used as a trade-mark on goods or packages; and the invention consists in the arrangement of certain letters of the alphabet, in combination with a view of a dog's head, the same being executed in an ornamental and artistic manner, forming, with the letters, a monogram, and enclosed within a circle or ring, as hereinafter described.

The drawing represents the design, in which the letters U M C C will be distinguished with a small o to denote "Co.," by which o the two C's are linked together.

The U is marked *a*, elongated vertically, and composed of heavy lines with slotted oblique T-ends.

B is the M, with curved base, as seen at *c c*. The upper portions of the M are curved, and terminate in scrolls, as seen at *d d*.

The two C's, denoting "Cartridge" and "Company," are placed so as to cross the other letters and each other, both being somewhat elongated, and are marked respectively E and F.

E is elongated horizontally, and has a heavy serrated back, as seen at *g*. The extreme portion of the back forms an obtuse angle.

The upper limb passes over the left limb of the M,

under the U, and under the right limb of the M, with a scroll near its end, as seen at *h*.

The lower limb passes under the left limb of the M, and through a diamond-shaped loop, formed by the light or middle lines of the M, as seen at *i*, over the U and the other limb of the M.

The other C, marked F, is elongated vertically. Its upper portion passes over the U, and is interlaced with the M, and with the other C, in a manner similar to that already described.

Its extreme upper and lower portions terminate in points *j j*. The upper point passes between the limbs of the U, and the lower point laps over the bottom end of the U, as seen at *k*.

L denotes the dog's head, which is seen projecting through the M, within the curves of the two C's, and over the U.

M represents the o, which is seen between the limbs of the U, linking the two C's together.

P represents the circle or ring by which cipher or trade-mark is enclosed.

The cipher, composed of the letters described, forms a monogram denoting the "Union Metallic-Cartridge Company."

Having thus described my invention,

I claim as new, and desire to secure by Letters Patent—

The design for a trade-mark, as shown and described.

The above specification of my invention signed by me, this 8th day of September, 1868.

AMORY EDWARDS.
